UNITED STATES PATENT OFFICE.

JAMES H. DOOLEY, OF EAST ORANGE, NEW JERSEY, ASSIGNOR TO ADDOMETER CORPORATION, OF NEW YORK, N. Y., A CORPORATION OF DELAWARE.

SIGNAL-PRINT FOR CALCULATORS.

1,182,532.

Specification of Letters Patent.

Patented May 9, 1916.

Application filed May 13, 1915. Serial No. 27,800.

To all whom it may concern:

Be it known that I, JAMES H. DOOLEY, a citizen of the United States, and a resident of East Orange, in the county of Essex and State of New Jersey, have invented certain new and useful Improvements in Signal-Prints for Calculators, of which the following is a specification.

This invention relates to means for printing signal characters or special marks in an adding machine adjacent special amounts that are printed on the record sheet and also to indicate other facts such as that an item or number has been accumulated, but not 15 printed on the record.

In a Patent No. 1,092,497, granted April 7, 1914, to J. C. Lotterhand, is set forth and claimed means that upon depression of a special key, will cause, upon subsequent operation of the handle or motor shaft, a special operation of the machine different from the normal listing and accumulating of items, and which printing of the signal is effected at once upon the depression of the 25 special key, and previous to any operation or movement whatever of the handle or motor shaft. In such construction a bar is provided that is normally tensioned and upon initial depression of one of the keys 30 the bar is released and advanced by such tensioned means a distance differing according to the key depressed. And in such construction a further depression of the key causes the swinging of such bar and thereby effects 35 the printing operation of the signal; which signal device is selected and positioned at the said first movement of the bar by its tensioned device.

In the present invention the multiple 40 printing member is connected with means that are positively actuated by the depression of one of the special keys of the machine, that is, is energized and actuated by the actual depression of the key stem, in 45 contra-distinction to the structure of the said patent wherein the positioning means for the printing member has a spring or other member that is energized during the main operation of the machine, to be subsequently rendered operative by the depression 50 of the key stem. In the present invention further, both the selecting means by which the printing member is positioned, and the actual impression member or ham- 55 mer, are positively energized or actuated

by and during the depression of one of the special keys. And such operation takes place during the depression movement of the key stem, so that by the time the key stem has been depressed its full and proper distance, the type carrier is positioned, and the hammer is drawn back to be tensioned and released to make the impression. 60

In the accompanying drawings illustrating one embodiment of my invention, Figure 1 shows a side plate of an adding machine with the parts relating to the present invention connected therewith. Fig. 2 is a plan view partly broken, of the parts shown in Fig. 1. Fig. 3 is a view of the parts 70 shown in Fig. 1, with certain members in intermediate position. Fig. 4 is a side elevation showing the printing hammer and parts connected therewith to operate the same; and Fig. 5 is a rear view, partly 75 broken, of the parts shown in Fig. 1.

The machine as shown is somewhat of the form set forth in the said patent to J. C. Lotterhand. The left hand side plate 6 is shown that is suitably supported in upright 80 position. At the rear is suitably supported a platen 7, to receive impressions from the usual printing hammers of the machine, not shown. Between the hammers and the platen are arranged type carriers that are 85 caused to print on the platen by the hammers. A type carrier 8 having four type 9, 10, 11 and 12 mounted thereon, is suitably supported for vertical movement adjacent the platen, to bring any one of these 90 four type opposite the platen. The carrier 8 has an extension 13 pivoted to one arm 14 of a bent lever 14-49 secured to a shaft 15 that swings in the supporting plate of the printing mechanism, and in the plate 95 6, and projects out beyond the latter. This shaft 15 at the outer end is secured to an arm 17 extending upward and which is pivoted to a bar 18 extending longitudinally outside of the plate 6. At its front end the 100 bar 18 is supported by a roller 19 carried by the plate 6 and engaging a recess in the lower part of the bar. By this means the bar has a limited movement rearward that will swing the arm 17 to rock the shaft 15, 105 and through the bent lever 14 will serve to elevate the type carrier.

In the views are shown four special key stems 20, 21, 22 and 23, that may represent respectively the total, the sub-total, the non- 110

print and the non-add keys; for example, as set forth in the said patent to J. C. Lotterhand, and in another patent to J. C. Lotterhand No. 1,102,157. Each of these key stems is shown as provided with a pin, as 24, 25, 26 and 27 respectively. The bar 18 is shown as being drawn forward normally by a spring 28 until the carrier 8 is in its lowermost position with its uppermost type 12 opposite the axis of the platen 7. In the upper edge of the bar 18 is a recess having a cam or inclined edge 29 that in the normal position of the bar just described, will lie beneath the pin 27 on the stem 23. On depression of this key the pin will strike the inclined edge and force the bar 18 rearwardly, until the pin passes beyond this cam and into a recess 30 in the bar 18. These parts of the bar are so arranged that the bar will thereby be given a rearward movement against the tension of the spring 28, and through arm 17, shaft 15 and arm 14, the carrier will be lifted a maximum distance, so that the lowermost type 9 is now brought to the printing position opposite the platen. The bar 18 also has a recess 31, at the rear of which is a cam or incline 32, arranged to coöperate with the pin 26 on the key stem 22. When this latter stem is depressed the bar 18 will move rearwardly from its normal forward position, but as will be seen from Fig. 1 the amount of incline engaged by the pin will be less than that coöperating with the pin 27, and hence the bar will move a less distance rearwardly. And this will serve to elevate the type carrier 8 sufficiently only to bring the type 10 to the printing position. Similarly a recess 33 is provided to coöperate with the pin 25 of the key stem 21, and has a short incline or cam 34. When the stem 21 is depressed the side bar will travel rearwardly a less distance than caused by either of the said key stems 22 or 23, and the carrier 8 will rise only sufficiently to bring the type 11 to the printing position. The type carrier 8 in its normal position has the fourth type 12 in the printing position; and this character corresponds with the fourth key 20. Therefore there is no need of shifting the type carrier on depression of the key stem 20.

A hammer 35 is shown mounted to swing on a suitable pivot 36 to strike one of the four type respectively in the four described positions of the carrier 8, and cause the type to make an impression on the platen. The hammer has a beak 37 on its lower end that is engaged by a trigger 38, pivotally mounted on one arm 39 of a bent lever, mounted on a fixed pivot 40. A spring 41 is secured to a lug 42 on an arm of the trigger and presses it against the beak 37 in its normal position. But when the bent lever is swung 65 the upper arm thereof causes a movement

bodily of the trigger 38, and the latter engaging the hammer will swing it back to tension its energizer lever 43. At the further movement of the arm 39 the trigger will have its arm 44 brought to engage a fixed pin 45, that will swing the trigger on its pivot, to cause it to release the hammer. Thereupon the hammer will be impelled by its energizer lever 43 to strike a blow on the positioned type in the carrier 8. To 75 actuate the bent lever having the arms 39 and 53 from the depression of the key stems, I pivot a lever 47 on the side bar 18, at 48

The upright arm 49 of the bent lever 14-49 carries loosely a shaft 50, which 80 shaft extends outwardly and forms the pivot connection between the arm 17 and the bar 18. When the bar 18 moves rearwardly to swing the arm 17 and shaft 15, obviously the shaft 50 will be bodily moved 85 to the rear. This shaft 50 has an arm 51 secured thereto, that projects forward and engages a pin 52 on the arm 53 that forms a bent lever with the said arm 39. A spring 54 serves to draw the arm 53 and parts connected therewith downwardly to cause the pin 52 to retain contact with the arm 51. At its outer end the shaft 50 is rigidly secured to an arm 55 carrying a pin 56, that engages the rear slotted end 57 of the side 90 lever 47. The spring 28 is not connected directly to the side bar 18, but to the lever 47 and hence tends to draw its forward end upward that will cause it to engage the pin 24 on the total key 20 in the normal position. When this key stem 20 is depressed the forward end of the lever 47 will move downward and the rear end will swing up and rock the arm 55 and swing the shaft 50. This will swing the arm 51 upward to 100 rock the bent lever 39-53, and the latter through the trigger 38 will first retract the hammer and then trip it to make an impression. It will be understood that the total key has no connection with the side 105 bar 18 that positions the type carrier, and this is because the carrier is normally held with the type 12 corresponding to the total, in the printing position. The swinging lever 47 on the side bar 18 is so constructed 110 that it will be engaged by each of the pins 25, 26 and 27 on the other three key stems when depressed. But the lever 47 is not engaged by these pins until the pin has first engaged its coöperating cam edge on the 115 side bar 18 and caused the advance rearward of the bar 18, and thereupon the pin moves downward into the recess beyond the cam. At such stage the pin will not cause further rearward movement of the bar 18, but will 120 now and for the first time engage the lever 47 to rock it on the bar 18, thereby causing the trigger to cock and release the hammer. It will be understood that at the initial 125 part of the depression of either one of these 130

three key stems (except the total), the side bar 18 is at once engaged and moved rearwardly, carrying with it the lever 47 that is pivoted thereon. Only after the pin on the key stem has caused the full rearward movement of the side bar 18, does the pin come into engagement with the lever 47. And the continued depression of the key stem causes the pin to swing the lever 47, 5 to cock and trip the hammer. When the key stem depressed has been released and returned to normal position, the spring 28 will return the side bar 18 and lever 47 to their normal forward position. This spring 10 will also swing the lever 47 to its normal position that will return the parts connected therewith for operation of the trigger. The spring 54 connected with the bent lever 53-39 will swing it back and cause 15 the trigger to reengage the beak of the hammer 35.

It will thus be seen that the type carrier is positively actuated or moved to position the type, from and by the depression of one 25 of the special key stems. This is done against the tension of a spring that will return the carrier and connected parts to normal position when the key stem is returned to its normal position. It will also 30 be understood that by the actual depression of the key stem, the hammer is first drawn back and energized, and by the continued movement of the key stem the hammer is released to make the impression. The 35 several parts are absolutely independent of any operation of other parts of the machine for any movement or resetting whatsoever.

Having thus described my invention, what I claim is:

40 1. In a calculator, having the usual accumulating and printing means, a main operating device for said means arranged to set up selected items upon the normal operation of such device, and special keys adapted to cause special operations of the accumulating or printing means or of both on operation of the main operating device, the combination of signal printing means connected with the special keys and organized 45 and constructed to be positively energized and actuated by and during the depression of the special key, whereby the signal printing is effected at the conclusion of the depression of the special key and previous to the operation of the said main operating device.

50 2. In a calculator, having the usual accumulating and printing means, a main operating device for said means arranged to 55 set up selected items upon the normal operation of such device, and special keys adapted to cause special operations of the accumulating or printing means or both, on operation of the main operating device, the combination of signal printing means con-

nected with the signal keys and including selecting and impression means each organized and constructed to be positively energized and actuated by and during the depression of the signal key, whereby the signal printing is effected at the conclusion of the depression of the special key and previous to the operation of the said main operating device. 70

3. In a calculator, having the usual accumulating and printing means, a main operating member for said means arranged to set up selected items upon the normal operation of such device, and special keys adapted to cause special operations of the printing means or both on operation of the main operating device, the combination of signal printing means connected with the signal keys and including selecting and impression means, the selecting means being 80 organized and constructed to be positively energized and actuated by and during the depression of the signal key, whereby the signal printing is effected at the conclusion of the depression of the signal key and previous to the operation of the said main operating device. 85

4. In a calculator, having the usual accumulating and printing means, a main operating member for said means arranged to 90 set up selected items upon the normal operation of such device, and special keys adapted to cause special operations of the accumulating or printing means on operation of the main operating device, the combination of signal printing means connected with the signal keys and including impression and selecting means, the impression means being organized and constructed to be positively energized and actuated by and 95 during the depression of the signal key, whereby the signal printing is effected at the conclusion of the depression of the signal key and previous to the operation of the said main operating device. 100

5. In a calculator, having the usual accumulating and printing means, a main operating member for said means arranged to set up selected items upon the normal operation of such device, and special keys 115 adapted to cause special operations of the accumulating or printing means on operation of the main operating device, the combination of signal printing means connected with the special keys and including impression and selecting means, the impression means being both tensioned and released by and during the depression of the signal key, whereby the signal printing is effected at the conclusion of the depression of the 120 special key and previous to the operation of the said main operating device.

6. In a calculator, having the usual accumulating and printing means, and special keys adapted to cause special operations of 130

one or of both said means, the combination of a type carrier provided with a set of type corresponding with the special keys, a bar connected with the carrier, means connecting the bar and the special keys whereby the bar is positively advanced by each of the keys when depressed and for a different relative distance to position the carrier according to the key depressed, a lever carried by said bar and arranged to co-operate with the said key stems, and an impression member connected with said lever and arranged to effect the impression at the final movement of the key stem and 15 after the bar has positioned the type carrier.

7. In a calculator, having the usual accumulating and printing means, and special keys adapted to cause special operations of one or of both said means, the combination of 20 a type carrier provided with a set of type corresponding with the special keys, a bar connected with the carrier, means connecting the bar and the special keys whereby the bar is positively advanced by each of 25 the keys when depressed and for a different relative distance to position the carrier according to the key depressed, a lever carried by said bar and arranged to co-operate with the said key stems, an impression member connected with said lever and arranged 30 to effect the impression at the final movement of the key stem and after the bar has positioned the type carrier, and a spring connected with the lever and bar whereby 35 both members are returned to normal position at once upon disengagement of the key and said members.

8. In a calculator, having the usual accumulating and printing means, and special 40 keys adapted to cause special operations of one or of both said means, the combination of a type carrier provided with a set of type corresponding with the special keys, a bar connected with the carrier, means 45 connecting the bar and the special keys whereby the bar is positively advanced by each of the keys when depressed and for a different relative distance to position the carrier according to the key depressed, a 50 spring arranged to retract the bar as soon as released from the said key, an impression member, and means for causing the depression of the key stem to actuate the impression member.

55 9. In a calculator, having the usual accumulating and printing means, and special keys adapted to cause special operations of one or of both said means, the combination of a type carrier provided with a set of type 60 corresponding with the special keys, a bar connected with the carrier, means connecting the bar and the special keys whereby the bar is positively advanced by each of the keys when depressed and for a different 65 relative distance to position the carrier ac-

cording to the key depressed, a lever pivotally carried by said bar and arranged to be swung by the key stems, a hammer arranged to cause printing of the type carrier, and means connecting the hammer and said lever 70 whereby the swinging of the lever by the key stem will first retract the hammer and then swing it to print.

10. In a calculator, having the usual accumulating and printing means, and special 75 keys adapted to cause special operations of one or of both of said means, the combination of a type carrier provided with a set of type corresponding with the special keys, a bar connected with the carrier and arranged 80 when reciprocated to position the carrier to bring the different type to printing position, a pin on each of the special keys, said bar having a series of cams each arranged to co-operate with one of said key pins 85 whereby on depression of any one of the keys the pin will engage the cam and cause advance of the bar to shift the carrier, means for retracting the bar when released from the key pins, a hammer for causing 90 the type in the carrier to print, and means connected with the hammer arranged to co-operate with the key pins whereby on the further depression of the key after shifting said bar the hammer is caused to make the 95 impression.

11. In a calculator, having the usual accumulating and printing means, and special 100 keys adapted to cause special operations of one or both of said means, the combination of a type carrier provided with a set of type corresponding with the special keys, a bar connected with the carrier and arranged 105 when reciprocated to position the carrier to bring the different type to printing position, a pin on each of the special keys, said bar having a series of cams each arranged to co-operate with one of said key pins whereby on depression of any one of the keys the pin will engage the cam and cause 110 advance of the bar to shift the carrier, means for retracting the bar when released from the key pins, a lever pivoted on the said bar and arranged to be engaged by the pins on the stems after the pins have 115 caused the advance of the bar, a hammer arranged to cause printing of the type in the carrier when positioned, and means connecting the hammer with said lever whereby by the said swinging of the lever by the key 120 pin will cause the hammer to make an impression.

12. In a calculator, having the usual accumulating and printing means, and special 125 keys adapted to cause special operations of one or both of said means, the combination of a type carrier provided with a set of type corresponding with the special keys, a bar connected with the carrier and arranged 130 when reciprocated to position the carrier to

- bring the different type to printing position, a pin on each of the special keys, said bar having a series of cams each arranged to co-operate with one of said key pins whereby 5 on depression of any one of the keys the pin will engage the cam and cause advance of the bar to shift the carrier, means for retracting the bar when released from the key pins, a lever pivoted on said bar and arranged 10 to be swung by said key pins on depression of the key after advance of the bar thereby, a hammer arranged to cause the type in the carrier to print, an energizer for said hammer, a trigger connected 15 with said hammer, and means connecting said trigger and said lever on the bar whereby the swinging of the lever by the key pin will swing the trigger and cause the hammer to first retract and then be impelled by the energizer to effect an impression.
13. In a calculator, having the usual accumulating and printing means, and special keys adapted to cause special operations of 25 one or both of said means, the combination of a type carrier provided with a set of type corresponding with the special keys, a bar connected with the carrier and arranged when reciprocated to position the carrier to 30 bring the different type to printing position, a pin on each of the special keys, said bar having a series of cams each arranged to co-operate with one of said key pins whereby on depression of any one of the keys the 35 pin will engage the cam and cause advance of the bar to shift the carrier, means for retracting the bar when released from the key pins, a lever pivoted on said bar and arranged to be engaged by the key pins at the 40 latter part of their movement after shifting the bar, a key separate from said special keys, a pin on the latter key independent of said bar but arranged to engage said lever to swing the lever on the bar, a hammer arranged 45 to strike the type in the carrier, and means connected with said bar lever and the hammer, whereby the swinging of the lever by any of said keys will cause the hammer to retract and then make an impression.
- 50 14. In a calculator, having the usual accumulating and printing means, and special keys adapted to cause special operations of one or of both of said means, the combination of a type carrier provided with a set of type 55 corresponding with the special keys, a shaft pivoted at the rear of the machine, an arm fast on said shaft and pivotally connected with the carrier, an upright arm on said
- shaft, a bar pivoted to said arm to move back and forth to swing the arm and position the carrier, a set of special keys arranged adjacent said bar, a pin on each key, said bar having cams one to co-operate with each key pin to shift the bar and position the carrier, a lever pivotally carried by said 60 bar and arranged to be swung by said key pins after the pins have advanced the bar, a second arm on said shaft, a shaft carried by said two arms and connected with said bar to be bodily shifted when the bar is advanced, an arm on the second shaft connected with said lever on the bar to be 65 swung thereby to rock the second shaft, a crank arm fast on the second shaft, a lever swung by the second arm, a trigger carried by said latter lever, a hammer engaged by said trigger to strike the carrier type, and an energizer for said hammer to cause it to print, said trigger being advanced by its 70 said connecting members from the swing of 80 the side bar lever to cause the hammer to first retract and then make an impression.
15. In a calculator, having the usual accumulating and printing means, and special keys adapted to cause special operations of 85 one or of both said means, the combination of a type carrier provided with a set of type corresponding with the special keys, means connecting the carrier and the special keys whereby the carrier is positively advanced 90 by each of the keys when depressed and for a different relative distance to position the carrier according to the key depressed, an impression member, and means for causing the depression of the key stem to actuate the 95 impression member.
16. In a calculator, having the usual accumulating and printing means, and special key stems adapted to cause special operations of one or of both said means, the combination of a type carrier provided with a set of type corresponding with the special keys, a member connecting with the carrier and arranged to be directly operated upon by said key stems whereby the carrier is 100 positively advanced by each of the key stems when depressed and for a different relative distance to position the carrier according to the key depressed, said member and the key stems having co-operating portions comprising a cam portion on one member arranged to engage a shoulder portion on the other member to advance the said member directly from the depression of the key stem.

JAMES H. DOOLEY.
